UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR AN ANDIRON.

SPECIFICATION forming part of Design No. 36,047, dated September 9, 1902.

Application filed July 29, 1902. Serial No. 117,567. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Andirons, of which the following is a full, clear, and exact description, reference being had to the accompanying drawing, in which is represented a pair of andirons duplicates of each other and each embodying the design.

The leading features of the design consist of a standard having at its top and bottom a bulbous open-work formation. Extending from the top bulb is a portion designed to represent the conventional form of lily. Below the lower bulb of the standard is a square

portion having a pyramidal piece extending from its lower surface. Extending from the sides of the square bottom of the standard are scroll or S-like portions constituting the feet of the andiron, and extending from the rear of the standard is an angled bar forming the rear support for the andiron.

I claim—

The ornamental design for an andiron as herein shown and described.

In testimony whereof I have hereunto set my hand in the presence of two subscribing witnesses.

THOMAS M. DUDGEON.

Witnesses:

C. L. SAXTON,
E. A. PARSONS.
